GUTTER SUPPORT AND METHOD OF MAKING SAME

Max Rachlin, Flushing, N. Y.

Application November 17, 1939, Serial No. 305,033

16 Claims. (Cl. 29—150)

This invention relating as indicated to a gutter support and method of making same is more particularly directed to an eaves trough supporting device comprising a circle and a shank. 5 These terms are well known in the art and have the following meanings.

A shank comprises a member having two angular portions, one of which is adapted to lie upon the roof sheathing the other of which is adapted to extend in a vertical plane so as to receive the circle. The circle comprises an arcuate member which is approximately a half circle in which the gutter is adapted to be received. There are many forms of shanks and circles and 15 the invention contemplated herein is directed toward a novel form of both the shank and the circle as well as a novel method of manufacturing the same.

Heretofore roofers have employed shanks and 20 circles formed of material having a channel section. This is generally referred to in the art as channel and will be so called hereinafter. Channel has two rather serious disadvantages, the most important of which is that its cost is 25 relatively high. A second disadvantage is that the angularly related portions of the shank must extend in planes at right angles to each other which necessitates twisting the channel at a localized point. It is also somewhat difficult in 30 forming a circle of channel to obtain an accurate bend since one flange of the channel must be compressed while the other flange is expanded.

I propose to eliminate the above difficulties 35 and to reduce the cost of gutter supports by forming shanks and circles from material having a circular cross section such as wire. The cost of wire is less than that of channel so that my novel gutter support represents a saving in cost 40 of materials.

I propose to flatten wire and this in itself 45 imparts strength since something in the nature of a forging operation takes place. In actual tests it can be shown that a shank and circle made by flattening wire is far stronger than similar shanks and circles cut from sheet metal or formed from channel. It will also be seen 50 that in the formation of the shank it is not necessary to twist the metal which may occasion crystallization and cause the shank to break at the point where it is twisted.

It is therefore an object of the present invention to provide a gutter support and method of making same employing wire as a starting material and comprising a shank and a circle.

To the accomplishment of the foregoing and related ends, said invention, then, consists of the means hereinafter fully described and particularly pointed out in the claims; the annexed drawing and the following description setting forth in detail one method and one product constituting, however, but one of various applications of the principles of my invention. 5

In the accompanying drawing:

Figure 1 is a side elevation showing the circle 10 attached to the shank and in normal operative position.

Figure 2 is a plan view taken from above of Figure 1.

Figure 3 is a horizontal section taken on line 15 3—3 of Figure 1.

Figure 4 is a perspective view of the wire from which the shank is formed.

Figure 5 is a perspective view of the wire 20 from which the circle is formed.

Figure 6 is a detail elevation of part of a circle showing a modification of the means for interlocking the circle with the shank.

Referring now to the drawing and more particularly to Figure 1, it will be seen that I have 25 provided a shank consisting of angularly related portions 11 and 12 which are connected by means of the portion 10. This shank is formed by cutting a desired length of wire W and then bending the same into the configuration shown 30 in Figure 4. The portion 11 is then formed by flattening dies. This portion can be a tapered flat arm, the thickness diminishing from the connecting portion 10 toward the end of such portion 11. I prefer however, to impart a channel shape as shown in Figures 1 and 2, since 35 this eliminates the necessity of counter sinking perforations 13 and 14. If desirable the channel shape and perforations may be formed in a single step or the perforations can be imparted after formation of the groove 11'. The shank is then inserted in another press which imparts the groove 12' and may at the same time perforate such groove as desired so that fastening means may be inserted through the holes 15. 40

From an inspection of Figure 1 it will be seen that the portion 11 extends in a plane at right angles to the sheet upon which the figure is drawn and further that the portion 12 extends in a plane parallel to the plane of the drawing. 50 However, no twisting action has taken place since the connecting portion 10 remains in its original shape. The portions 11 and 12, due to the pressing operations, have added strength since the metal is worked or forged during such op- 55

eration. The portion 11 of the shank is attached to the sheathing R of the roof by driving fastening means through the perforations 13 and 14 as desired. The shank is now ready to receive 5 the circle.

The circle comprises an arcuate member 16 formed from the wire W' shown in Figure 5. This circle is made by cutting a desired length of wire and then bending such wire to the shape shown in Figure 5. At the same time the left hand end of the wire as shown in Figure 5 is rebent or bent upon itself to ultimately provide the hook 25. The wire W' is then placed in a press and flattened whereby the configuration shown in Figures 1 and 2 is obtained. In order to provide a relatively wide seat for the gutter S the inner edge 23 of the circle has corrugations 22 formed therein. These corrugations may be formed when the wire W' is flattened, or if desirable, they may be formed subsequently. It will be seen that the corrugations provide a seat which is approximately three times as wide as the remaining portion of the circle 16. In order to interlock the circle with the shank I have provided a projection 19 adapted to snugly engage the groove 12' of the shank. This projection has perforations 20 therein through which a fastening bolt 15 is adapted to project. The bolt 15 is provided with a slotted head 17 and the circle may assume any one of a large number of positions as desired by the roofer. As a further means of anchoring the circle to the shank I have provided a small projection 21 on the circle adapted to engage the outer vertical edge of the shank 12.

In the modification shown in Figure 6 instead of a single projection 19 I have provided a series of small projections 26 with perforations 27 between such projections. The working of the wire by formation of the projections further strengthens the wire instead of weakening the circle which is occasioned by forcing a portion of flat metal out of its plane.

From the foregoing description it will be seen that I have provided a novel form of shank and circle formed entirely from material having a cross section such as wire. It is well known that channel costs more than wire so that my gutter support represents a saving in base materials.

It will also be observed that my gutter support is stronger than gutter supports containing the same weight of metal as known in the prior art because a flattening or pressing operation imparts strength. It will also be seen that the circle 16 can be elevated higher on the vertical leg 12 of the shank because the metal connecting the two angular portions of the shank is not twisted, as is the case where the shank is formed of channel.

It will also be seen that an advantage is derived from tapering the portion 11 of the shank since so-called hard shingles will not be broken due to the taper, and so-called soft shingles will not show through due to the taper.

It will also be seen that neither the circle nor the shank is weakened in any way since neither member is twisted.

The preceding description involves what is believed to be an entirely new method of making a gutter support and particularly a support of the shank and circle type. Primarily, this method eliminates the necessity and expense of forming metal into a channel shape while at the same time producing a stronger support.

Finally, it is important to note that in order

to twist flat metal of channel a relatively soft metal must be employed. In the present case, however, wire of any hardness can be used since twisting and consequent crystallization is entirely eliminated.

It is to be understood that I may employ wire to form a circle which is not entirely flat and it is also to be understood that I may employ wire which initially has shapes other than circular cross section with the exception of course of flat strip material.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:

1. A gutter support comprising a circle and a shank, said shank being formed of flattened wire and said circle being formed of flattened wire and being secured to said shank.

2. In a gutter support comprising a shank and circle; a shank formed from a section of wire and having two portions extending angularly with respect to each other, one of said portions being channel shaped in cross section.

3. In a gutter support comprising a shank and circle; a shank formed from a section of wire and having two portions extending angularly with respect to each other, one of said portions being channel shaped, in cross section, the other portion tapering in thickness toward its end.

4. In a gutter support comprising a shank and circle; a shank formed from a section of wire and having two portions extending angularly with respect to each other, that part of said shank connecting said portions being substantially round in cross section, one of said portions being channel shaped in cross section.

5. In a gutter support comprising a shank and circle; a shank formed from a section of wire and having two portions extending angularly with respect to each other, that part of said shank connecting said portions being substantially round in cross section and both of said portions being apertured to receive fastening means, one of said portions being flattened and tapering in thickness there being interlocking means on said shank and circle.

6. In a gutter support comprising a shank and circle; a shank formed from a section of wire and having two portions extending angularly with respect to each other, each of said portions having a flattened surface, said surfaces extending in planes at right angles to each other, said circle being formed from a section of wire and having portions thereof in engagement with one of said flattened surfaces.

7. A flattened gutter hanger circle formed from a material of circular cross section and having one end rebent, to form an open hook, there being a notch in the other end.

8. A flattened gutter hanger circle formed from a material of circular cross section and having an inner seat for a gutter, said seat being formed by bending portions of the flattened edge of said circle in opposite directions.

9. A gutter hanger circle, formed from flattened round stock and having an inner seat for a gutter, said seat comprising corrugations in the upper edge of said circle, and said circle being provided with means adapted to interlock with means on a shank.

10. A gutter hanger circle, formed from flattened round stock and having an inner seat for a gutter, said seat comprising corrugations in the upper edge of said circle, and said circle being provided with projections, said projections comprising one major projection adapted to be received in the groove of a channel shaped shank and a minor projection adapted to engage an outer surface of a shank.
11. A gutter hanger circle, formed from flattened round stock and having an inner seat for a gutter, said seat comprising corrugations in the upper edge of said circle and said circle being provided with projections, said projections comprising a series of spaced alined members adapted to be received in the groove in a channel shaped shank and a minor projection adapted to engage an outer surface of a shank.
12. In a method of making a gutter circle, the steps which comprise cutting a desired length of wire, bending said wire into substantially arcuate form, with one end of said wire bent upon itself, to provide a return bend support for the gutter, and then pressing said wire to form a flat circle.
13. In a method of making a gutter circle, the steps which comprise cutting a desired length of wire, with said wire bent into substantially arcuate form, then bending one end of said wire upon itself, to provide a return bend support for
14. A method of forming a gutter circle which comprises flattening a substantially arcuate piece of metal having a circular cross section to form a flat circle having an inner and an outer edge and then forming a gutter seat in said inner edge by crimping said inner edge.
15. A method of forming a shank, adapted to be used in an eaves trough supporting device, which comprises cutting a desired length of wire, then bending said wire so as to impart angularly related portions, then flattening one of said portions and then flattening the other portion in a plane at right angles to the plane of said first named portion and then forming such flattened portions into channel shaped portions.
16. A method of forming a shank, adapted to be used in an eaves trough supporting device, which comprises cutting a desired length of wire, then bending said wire so as to impart angularly related portions, then flattening one of said portions and then flattening the other portion in a plane at right angles to the plane of said first named portion and then forming such flattened portions into channel shaped portions and finally perforating such channel shaped portions.

MAX RACHLIN.
